STEAM BOILER

Otto Günther, Esslingen-on-the-Neckar, Germany, assignor to Maschinenfabrik Esslingen, Esslingen-on-the-Neckar, Germany

Application April 29, 1933, Serial No. 668,509
In Germany December 18, 1930

4 Claims. (Cl. 122—235)

This invention relates to improvements in the design of steam boilers for motive power, f. i. rail-cars, steam buses, small locomotives, etc. in which the fire box is substantially built of steam generating and water carrying tubes.

An object of this invention resides in the provision of a new and improved water-tube boiler design in which the heat is substantially transmitted by radiation to tubes lining the fire box, and only a comparatively small part of the heat is transmitted by convection.

An object of this invention resides in the provision of a water-tube boiler having such arrangement of the water and steam carrying tubes as to assure a maximum of heat transfer in a very small space.

An object of this invention resides in the provision of an improved water-tube boiler design wherein the steam drums are supported by down comer tubes.

An important object of this invention resides in the provision of a water-tube steam boiler consisting of a fire box substantially built of heat absorbing tubes, convection tubes and water and steam drums arranged so that the steam drums are supported by down comer tubes and said down comer tubes are connected to the fire box ring which supports the whole boiler.

An object of the present invention resides in the provision of an improved water-tube boiler for use in motive power plants consisting of steam and water carrying tubes and drums, arranged so that the drums have no independent connection with the car and can move freely under the influence of heat expansion conditions and the vibrations of the car and the forces due to inertia when the car is accelerated or slowed up.

An object of the present invention is the provision of a water-tube boiler consisting of drums and heat absorbing tubes for use in rail cars, locomotives and the like arranged so that the drums are supported by water carrying tubes having comparatively equal temperatures at all output conditions so that all parts can freely expand and contract and no stresses can be applied to the structure and particularly the joints by heat expansion conditions and vibrations of the car propelled by the steam generated in the boiler.

An object of this invention resides in the provision of an improved water-tube boiler for motive power plants as outlined in the foregoing object and whereby the down comer tubes supporting the heavy drums are so arranged that only tensile and compression stresses are created with-

in the individual tubes forming the support structure.

Further and other objects of the present invention will be hereinafter set forth in the accompanying specification and claims and shown in the drawing which, by way of illustration, shows what I now consider to be a preferred embodiment of the invention.

In the drawing:

Fig. 1 is a cross-sectional view of the boiler with the tubes forming the side wall partly broken away.

Fig. 2 is a vertical sectional view along line A—B of Fig. 1 with the tubes forming the rear wall of the fire box partly broken away.

Fig. 3 is a vertical sectional view along line C—D of Fig. 1 with the front brick work broken away.

While the invention is susceptible of various modifications and alternative constructions, I have shown in the drawing and will herein describe in detail the preferred embodiment, but it is to be understood that I do not thereby intend to limit the invention to the specific form disclosed but intend to cover all modifications and alternative constructions falling within the spirit and scope of the invention as expressed in the appended claims.

Referring to the exemplary embodiment of the invention, I designates the furnace the ceiling of which is formed by the brick arch 2. The rear wall of the furnace is formed substantially by the water tubes 4 which connect the fire box ring 3 with the drum 5. As can be seen on Fig. 1 of the drawing, the upper parts of the tubes 4 have a bow-like configuration. The drum 5 is connected to the drum 7 by the tubes 6 and is rigidly connected with and supported by the fire box ring 3 by way of the downcomer tubes 8, 9, and 11. The tubes 4 and some of the tubes 6 substantially form the radiation chamber 12. The circulation through this part of the boiler, which may be called the radiation boiler, is independent from that through the other parts 13 and 14 of the boiler. The preheated feed water circulates from the drum 15 via the overflow 16 into the drum 5 and therefrom through the downcomer tubes 8, 9, 11 into the drum 7 and into the fire box ring 3; from fire box ring 3 it passes through the heat absorbing tubes 4 and 6 respectively in which it is partly evaporated or returned to the drum 5. The drum 15 together with tube 17 and the drum 18 forms a further boiler unit 13 also having an independent circulation. The water which is preheated in the

boiler unit 14 enters through the overflow 19, the feed valve 20 and the strainer 21 the drum 15 and circulates from this drum through the front tubes 17a, the drum 18 and the rear tubes 5 17b back into drum 15. The boiler unit 14 with the collecting drum 22, the drums 23, 24 and 25 and the water tubes 26, 27 and 28 has three independent circulating cycles.

The downcomer tubes 8, 9, and 11 are outside 10 and protected from heat transmission by radiation or convection. They are arranged as a triangle, the base of which is formed by the fire box ring 3, and support the upper drums 5 and 15 which latter rests on the drum 5 by way of 15 the shoes 34. Cross pipes 10 interconnecting the downcomer tubes may be provided and arranged substantially parallel to that side of the fire box ring 3, which forms the base of the triangle. Such cross pipes considerably stiffen the triangle structure and practically completely prevent bending of the downcomer tubes under the influence of the weight of the boiler. Since the fire box ring is directly connected to the car frame, the drums 5 and 15 and the boiler unit 20 25 12 connected thereto are also directly supported by this frame. The horse-like triangle construction of the downcomer and support tubes 8, 9, 10 and 11 assures that only tensile and compression stresses are exerted on these tubes and the 30 connections or joints of the tubes with each other and with the fire box ring 3 and the drum 5.

Since the drum 5 receives only water from the boiler units 14 and 13 which are in series with respect to the water flow and the flow of the 35 heating gases, the water is already preheated almost to its evaporation temperature before it enters the boiler unit 12. For this reason, practically no temperature difference exists between the fire box ring structure, the support structure, the tubes 4 and 6 and the drum 5, and heat stresses are prevented in the system at practically all operating and load conditions.

To complete the description of the embodiment of my invention shown in the drawing, 29 40 45 50 55 60 65 70 75 80 85 90 95 100 105 110 115 120 125 130 135 140 145 150 155 160 165 170 175 180 185 190 is located at the upper corner of the triangle, said support structure definitely taking off all load from said heat absorbing tubes.

2. A tubular steam generator for vehicles having a fire box, a steam drum located substantially over said fire box and a header located substantially at the bottom of and surrounding said fire box, a plurality of straight downcomer tubes connected to said header and said steam drum, said downcomer tubes being located substantially in planes parallel to the direction of the movement of said vehicle, the downcomer tubes located in one plane spreading apart and forming, together with said header, a horse-like support structure for said steam drum adapted to absorb the forces of inertia occurring during the acceleration and slowing up of the vehicle, and water carrying tubes also located in said planes parallel to the direction of movement of the vehicle and interconnecting said downcomer tubes located in the same plane and increasing the rigidity of said support structure.

3. A tubular steam generator having a fire box, a steam drum located substantially over said fire box and a header located substantially at the bottom of and surrounding said fire box, a plurality of curved and flexible heat absorbing tubes connecting said steam drum and said header, a plurality of pairs of straight, rigid downcomer tubes connected to said header and said steam drum, said downcomer tubes of said pairs being located substantially in parallel planes and being spread apart to form, together with said header, the exclusive supporting structure for said steam drum and adapted to definitely maintain the distance between said header and said steam drum and the location of said steam drum with respect to said header.
